US00D973489S

(12) **United States Design Patent** (10) Patent No.: **US D973,489 S**
(45) Date of Patent: **** Dec. 27, 2022**

(54) **BOTTLE LABEL**

(71) Applicant: **Nicole Johnson**, Oakland Park, FL (US)

(72) Inventors: **Nicole Johnson**, Fort Lauderdale, FL (US); **Ruben Ferreira**, Weston, FL (US); **Alexis Novoa**, Fort Lauderdale, FL (US)

(**) Term: **15 Years**

(21) Appl. No.: **29/841,382**

(22) Filed: **Jun. 6, 2022**

Related U.S. Application Data

(60) Continuation-in-part of application No. 29/838,548, filed on May 13, 2022, which is a division of application No. 29/798,406, filed on Jul. 7, 2021, now Pat. No. Des. 951,769.
